HOOD SCOOP FOR A TRACTOR

John A. Gale, Wayzata, and Robert E. Haueter, Minneapolis, Minn., assignors to Toro Manufacturing Corporation, Minneapolis, Minn., a corporation of Minnesota

Filed Sept. 4, 1968, Ser. No. 13,396

Term of patent 14 years

Int. Cl. D12—14

U.S. Cl. D14—18

FIG. 1

FIG. 2

FIG. 3

FIG. 4

FIG. 5

FIGURE 1 is a left front perspective view of a hood scoop for a tractor embodying our new design;

FIGURE 2 is a top plan view thereof;

FIGURE 3 is a left side elevational view thereof, the other side having a corresponding appearance;

FIGURE 4 is a front perspective view thereof;

FIGURE 5 is a rear perspective view thereof.

The broken lines are shown for illustrative purposes only.

We claim:

The ornamental design for hood scoop for a tractor, substantially as shown and described.
